UNITED STATES PATENT OFFICE

133,196

DESIGN FOR LEATHER OR SIMILAR ARTICLE

Samuel Galper, New York, N. Y.

Application December 17, 1941, Serial No. 104,689

Term of patent 3½ years

To all whom it may concern:

Be it known that I, Samuel Galper, a citizen of the United States, residing at 80-27 188th Street, in the city of New York, in the county of Queens and State of New York, have invented a new, original, and ornamental Design for Leather or Similar Article, of which the following is a specification, reference being had to the accompanying drawing, forming a part thereof.

Figure 1 is a plan view of the face of my ornamental design for leather or similar article.

I claim:

The ornamental design for leather or similar article, as shown.

SAMUEL GALPER.
